(57) **CLAIM**

The ornamental design for a box, as shown and described.

DESCRIPTION

FIG. 1 is a perspective view of the box of our new design from the front, right, shown in a folded configuration; FIG. 2 is an elevational view thereof from the front, shown in the folded configuration;

FIG. 3 is an elevational view thereof from the rear, shown in the folded configuration;

FIG. 4 is an elevational view thereof from the left, shown in the folded configuration;

FIG. 5 is an elevational view thereof from the right, shown in the folded configuration;

FIG. 6 is a top plan view thereof, shown in the folded configuration;

FIG. 7 is a bottom plan view thereof, shown in the folded configuration;

FIG. 8 is a perspective view thereof from the rear, right, shown in an unfolded configuration;

FIG. 9 is an elevational view thereof from the front, shown in the unfolded configuration;

FIG. 10 is an elevational view from the rear, shown in the unfolded configuration;

FIG. 11 is an elevational view thereof from the left, shown in the unfolded configuration;

FIG. 12 is an elevational view thereof from the right, shown in the unfolded configuration;

FIG. 13 is top plan view thereof, shown in the unfolded configuration; and,

FIG. 14 is a bottom plan view thereof, shown in the unfolded configuration.

1 Claim, 8 Drawing Sheets
